POWER UNIT FOR A DRIVING MACHINE

Werner Schafroth, P.O. Box 247, Herrin, Ill., and Anthony E. Cairatti, Herrin, Ill., said Cairatti assignor to said Schafroth

Filed Oct. 19, 1964, Ser. No. 82,225

Term of patent 14 years

(Cl. D54—14)

FIG.1

FIG.2

FIG. 1 is a top plan view of a power unit for a driving machine showing our new design,

FIG. 2 is a side elevational view thereof,

FIG. 3 is a front elevational view thereof,

FIG. 4 is a rear elevational view thereof, and

FIG. 5 is a perspective view of the side opposite to that shown in FIG. 2.

The essential features of our design reside in the portions shown in solid lines.

We claim:

The ornamental design for a power unit for a driving machine, substantially as shown and described.
